(57) **CLAIM**

The ornamental design for a front bumper for an automobile, as shown and described.

DESCRIPTION

FIG. 1 is a front and left side perspective view of a front bumper for an automobile showing my new design;

FIG. 2 is a front elevational view thereof;

FIG. 3 is a top plan view thereof;

FIG. 4 is a left side elevational view thereof;

FIG. 5 is a bottom plan view thereof; and,

FIG. 6 is a right side elevational view thereof.

The broken lines in the drawings illustrate portions of the front bumper for an automobile that form no part of the claimed design.
